UNITED STATES PATENT OFFICE.

LEWIS R. FERGUSON, OF PHILADELPHIA, PENNSYLVANIA.

REINFORCED-CONCRETE PILE FOR MARINE WORK.

1,257,835.

Specification of Letters Patent. Patented Feb. 26, 1918.

Application filed March 10, 1917. Serial No. 153,981.

To all whom it may concern:

Be it known that I, LEWIS R. FERGUSON, a citizen of the United States, residing at Philadelphia, in the county of Philadelphia and State of Pennsylvania, have invented 5 certain new and useful Improvements in Reinforced-Concrete Piles for Marine Work; and I hereby declare that the following is a full, clear, and exact description thereof, 10 reference being had to the accompanying drawings, which form part of this specification.

This invention relates to the construction of reinforced concrete piles, columns and 15 the like for marine work and is particularly designed for use in the manufacture of piles to be used in or near salt water, and where such piles will be exposed to the action of damp salt air.

20 I have discovered that metal reinforced concrete piles as heretofore constructed when used for marine work crack and spall, and rapidly lose their strength and become dangerous because of their disintegration. 25 Such disintegration I have found occurs chiefly, if not solely, in reinforced concrete piles and the like used in foundations for marine structures in or near salt water. This disintegration of the piles I have 30 found follows the line of the reinforcement and always starts above the low water line and is most extensive about the high water line; and such cracking and spalling is due to 35 oxidization of the reinforcement; as I further found that the portions of the piles which are buried or submerged are not detrimentally affected as are the exposed portions of the piles above low water. This 40 disintegration has been attributed heretofore to causes other than the true one.

It has heretofore been considered by experts in concrete construction that the reinforcement should be embedded only an inch or two in the concrete, and that it would be 45 secure from oxidization and elemental action; and that any greater thickness of protective coating for the reinforcing bars would be unnecessary and undesirable. But I have discovered that practically all the reinforced 50 concrete piles or foundation columns in concrete structures along the Atlantic and Pacific coasts are deteriorating and giving way on account of the cracking and spalling above referred to produced by the action of 55 the damp salt air on the piles.

I have discovered that such cracking and

spalling and disintegration of the piles can be prevented or indefinitely retarded by so arranging the metal reinforcing that the portions thereof within the exposed portions of the piles, or that portion above low water when the pile is *in situ*, will be embedded in the concrete to a much greater depth than the portion of the reinforcing in the submerged part of the pile, and by 60 means of my invention there is obtained a layer of concrete preferably four or more inches in thickness between the metal reinforcement and the exterior surface of the pile. The great value of my invention will 65 be appreciated by those who understand the difficulty or impossibility of repairing or replacing disintegrated sections in the exposed portions of reinforced concrete piles.

In utilizing my invention, in the preferred 70 manner, the reinforcing members in the piles are bent or deflected inwardly at a point which will be near the low water mark when the pile is *in situ*, so that the reinforcing members in the exposed portion of the 75 pile shall be protected by a much greater thickness of concrete than the portions of the reinforcing in the submerged or buried part of the pile. This construction is particularly efficient where it is desired or necessary to keep the pile of a substantially uniform diameter throughout. In cases where it is feasible to enlarge the diameter of the exposed portion of the pile sufficiently to give the necessary thickness of concrete to 80 protect the reinforcing, the reinforcing 85 might extend straight throughout the pile.

I will explain the invention with reference to the accompanying drawings in 90 which:

95 Figure 1 is a sectional elevation of a reinforced concrete pile constructed in accordance with the invention.

Figs. 2 and 3 are transverse sections of such pile, taken respectively on lines 2—2 100 and 3—3 Fig. 1.

Fig. 4 is a vertical section through a modified form of pile; and

Figs. 5 and 6 are transverse sections of such pile, taken respectively on lines 5—5 105 and 6—6 Fig. 4.

The concrete pile may be of any desired form and dimension; as shown in Figs. 1 to 3 of the drawings the pile 1 may be formed in the usual manner of concrete, and is reinforced by a series of longitudinally disposed metal members or bars 2, with or without

spiral wrappings or hoops, which extend throughout the length of the pile. Heretofore in making piles such reinforcing bars have been embedded only from one to possibly two inches in the pile. A greater depth than this is considered unnecessary and undesirable, as customarily the strength of the pile is calculated on the cross sectional area bounded by the rods. While this is satisfactory for submerged concrete work, and in the submerged or buried portions of the pile, yet the exposed portions of such piles, when used in or near salt water, spall and disintegrate as above stated; and this is the direct cause of a great deal of trouble in concrete structures heretofore constructed.

In carrying out my invention, the reinforcing members 2 for the pile are bent or converged inwardly as shown at 2^a at the point that will be near mean low water when the pile is *in situ*, and then continued upwardly parallel as indicated at 2^b within the exposed or upper portion of the pile, above low water when *in situ*. By this arrangement the portion of the reinforcing in the exposed portion of the pile is embedded to a much greater depth in the concrete than the portion of the reinforcing in the lower buried or submerged part of the pile; I consider it preferable to have the upper portion of the reinforcing embedded to a depth of at least approximately four inches in the concrete; for the chlorin in the air will eventually penetrate even the best concrete piles as now constructed for a depth of one or two inches and reach and attack the metal reinforcement and corrode same thereby producing the dangerous spalling, cracking and disintegration of the piles above referred to. But my having the members of the reinforcing in the exposed portion of the pile covered by an exterior layer of approximately four inches or more of concrete the reinforcing will be indefinitely thoroughly protected from the action of the damp air, and the life of the pile will be indefinitely prolonged and its practical value greatly enhanced.

In the construction shown in Fig. 4 the lower or submerged portion of the pile may be formed as usual, and the reinforcing bars 2 can extend directly throughout the length thereof, and arranged as in the lower portion of the pile shown in Fig. 1; but the upper exposed portion of the pile is enlarged in diameter so as to thicken the concrete layer exterior to the reinforcing to a depth of approximately four or more inches.

In such construction; as shown in Fig. 4, the enlarged portion of the pile should begin at a point near low water level, as indicated at 1^a, and the enlarged portion should extend throughout the upper or exposed portion of the pile above low water when *in situ*, as indicated at 1^b in Figs. 4 and 6.

If desired the reinforcing members and the pile may be further strengthened by bonding hoops or wire 4 spirally wrapped around the reinforcing bars, as indicated in Figs. 1 and 4 of the drawings.

70

The essentially novel feature of the invention is protecting the reinforcing members in the upper or exposed portion of the pile above low water mark by an extra external thickness of concrete approximately four or more inches in thickness and sufficient to greatly retard or entirely prevent the action of damp salt air upon the portion of the reinforcement extending within the exposed portion of the pile above mean low water. 80 Such thickness of concrete has heretofore been considered unnecessary and even detrimental as regards the strength of the pile; but I employ such an extra thickness of concrete for an entirely different and novel purpose to wit, to protect the metal reinforcement against deterioration or oxidization by the action of the sea spray and salt air, which has heretofore and is now causing rapid disintegration of concrete piles and 90 columns in foundations of marine structures as heretofore constructed where such piles and foundations are subjected to sea spray and salt air; which disintegration is caused by the oxidizing or chemical action of the 95 moist sea air containing chlorin upon the embedded metal reinforcement. This action will penetrate to a depth of one or two inches in the concrete of even the very finest quality, which is sufficient to enable it to 100 attack and destroy the metal reinforcement as heretofore arranged in piles constructed in accordance with the at present accepted best engineering methods, but which action will be prevented by the use of my invention. 105

What I claim is:

1. A concrete pile for marine work having a plurality of longitudinally disposed reinforcing metal members embedded therein, the parts of said reinforcing members in the 110 portion of the pile above low water being protected by an external layer of concrete approximately four inches thick; and being much farther removed from the exterior surface of the pile than are the parts of the reinforcing members in the lower or submerged portion of the pile.

2. A reinforced concrete pile for marine structures having a plurality of longitudinally disposed metal reinforcing bars extending throughout its length, the parts of the bars within the upper part of the pile exposed to the atmosphere above low water when *in situ* being embedded in the concrete to a much greater depth than usual, and to 125 a greater depth than are the parts of the bars in the lower or submerged portion of the pile.

3. A reinforced concrete pile for marine work having metal reinforcing embedded 130

therein, said reinforcing being contracted at a point below the part of the pile exposed to the atmosphere when *in situ* so that the portion of the reinforcing in the portion of the pile above low water is much more deeply embedded in the concrete and is protected by a much thicker layer of concrete than is the portion of the reinforcing within the lower or submerged portion of the pile.

10 4. A reinforced concrete pile for marine work having a plurality of longitudinally disposed metal reinforcing members extending longitudinally thereof, said reinforcing members being inwardly bent or deflected at

a point below the part of the pile exposed 15 when *in situ* and the upper part of the pile being thickened or enlarged so that the parts of the reinforcing members above such bend and in the part of the pile above low water are more deeply embedded in the concrete 20 and protected by a thicker layer of concrete than are the parts of the reinforcing members in the lower submerged portion of the pile.

In testimony that I claim the foregoing as 25 my own, I affix my signature.

LEWIS R. FERGUSON.
